UNITED STATES PATENT OFFICE.

SPENCER OTIS, OF CHICAGO, ILLINOIS.

LOCOMOTIVE-TERMINAL FIRE-DRAWING STATION.

1,413,346.

Specification of Letters Patent. Patented Apr. 18, 1922.

Application filed September 28, 1921. Serial No. 503,809.

To all whom it may concern:

Be it known that I, SPENCER OTIS, a citizen of the United States, residing at Chicago, in the county of Cook and State of Illinois, have invented certain new and useful Improvements in Locomotive-Terminal Fire-Drawing Stations, of which the following is a specification.

In my Letters Patent No. 1,387,863, issued

10 August 16, 1921, I have described and claimed a locomotive terminal for railway systems, involving in its organization, among numerous other features, a terminal house provided with stations for locomotives, spur 15 tracks connecting said stations with a main track, charging apparatus associated with the respective locomotive stations, a conveyor for distributing material to the charging apparatus, and a fire disposal system 20 serving a plurality of locomotive stations in said house; said system comprising means for quenching hot coals, cinders, and ashes drawn from the locomotive in any one of the stations, means for conveying away the 25 quenched material from any one of the stations, and means for disposal of the material accumulated from all the stations; the illustrated means for performing these several functions consisting in water sprays associated with fire chutes, a cinder tunnel receiving the discharge from the several chutes and containing either a wheeled vehicle or an endless conveyor for advancing to an external point of discharge the material delivered thereto, and railway trackage leading 35 away from said external point so that a standard car might travel to and from the same in disposing of the accumulation delivered through the tunnel.

40 One object of the present invention is to provide the locomotive terminal with a fire disposal system which will salvage the values from the drawn fires, and which will facilitate such salvaging or reclamation by providing a special arrangement of cinder quenching and conveying means that will put the cinders in better condition for recovery of their values, particularly as regards cleansing of the unconsumed portion 45 of the fuel or removal therefrom of the ash which is reduced to a fine or light condition, and the accomplishment of this economically without contaminating the atmosphere in which the employees have to work.

50 Accordingly, one feature of the present invention consists in constructing the cinder

tunnel in the form of a trough adapted for the employment of water as a quenching bath and conveying vehicle, and having said tunnel deliver into a cinder well from which 60 the water, in flowing, will carry away the light ash and leave the coke or unconsumed cinders behind in condition for removal and delivery to a point of further consumption, or to an apparatus for further treatment 65 preparatory to such consumption.

Another object of the invention is to provide means for precipitating washings or light material, and collecting the quenching, conveying, and washing water, and constantly recirculating it through the system as a measure of economy in water consumption; and, to this end, another feature of the invention consists in providing a settling chamber for the wash water after it leaves 75 the cinder well, a sump to receive the water from said settling chamber, and a pump for delivering water constantly or at necessary periods of time from the sump to the head of the trough-like cinder tunnel. 80

Still another object of the invention is to provide means for reducing and conditioning the refined cinders that collect in the cinder well, and delivering concentrated values thereof for further consumption; and 85 to this end, another feature of the invention consists in providing a dredging means for lifting the cinders from the well, reduction apparatus receiving the cinders from the dredging means and breaking them up so 90 as to disengage the coke from the clinker, a clinker-separating means through which the reduced cinders are passed, and means for disposal of the separated coke and clinker to desired destinations, the former preferably 95 to the stoking hopper of a stationary furnace plant forming a part of the terminal equipment.

In the accompanying drawings—

Figure 1 is a ground plan showing the 100 layout of a locomotive terminal embodying the several features of the present invention.

Figure 2 is a plan view of the terminal house on an enlarged scale.

Figure 3 is a vertical longitudinal section 105 on the line 3^x—3^x of Figures 1 and 2.

Figure 4 is a plan view on a still larger scale of the cinder reclaiming apparatus; and

Figure 5 is a vertical transverse section 110 on the line 5^x—5^x of Figures 1, 2, and 4.

Referring to Figure 1, 6 represents a loco-

2

motive terminal house having coal storing and delivering hoppers 7, fire drawing and quenching pits 8^a each communicating with a cinder tunnel 8 extending beneath and serving a plurality of locomotive stations through said pits, a stationary steam power plant 9, and a cinder salvaging apparatus 10. Outside of said terminal house are main tracks 11 diverging through suitable 10 spurs into coal supply tracks 12 and cinder loading tracks 13; and within the house are locomotive station tracks 14. Such additional tracks as may be desired are provided either within or without the house, 15 such, for instance, as an outside through track 15 and inside repair section tracks 16. The terminal house may also be provided with necessary working facilities, such as gib-cranes 17 and inspection pits 18 in 20 connection with the repair section track 16, also gib-cranes 19 adjacent the station track 14 beyond the ash pits 8^a, see Figure 2.

The ash tunnel 8 extends transversely beneath and communicates through the ash pits or openings 8^a with a sufficient number 25 of locomotive stations to avoid the necessity of any locomotive waiting for an antecedent locomotive to surrender a fire drawing station. Said cinder tunnel extends to the 30 cinder salvaging apparatus 10 where it merges, through a curve 8^b, with the cinder well 20 forming part of said apparatus; and, as shown in Figure 5, the tunnel is graded or inclined so as to develop a current or 35 flow to water delivered therein that will be effective in washing onward to the cinder well 20 the fire materials deposited through any one of the openings 8^a. From cinder well 20, water flows over a partition 21 into 40 the settling chamber 22, carrying the light ash with it into said chamber, where the ash settles and remains behind while the water escapes through a screened wall 23 into the sump 24. From sump 24 water is removed 45 by pump 25 and returned through pipe 26 to the head of the cinder tunnel 8 where it is delivered in sufficient volume, considering the grade or inclination of the tunnel, to maintain a quenching body in the 50 bottom of the trough-like tunnel at the time of drawing the fire, also a body of water sufficient in volume and in flow to wash the fire material to the cinder pit 20, as before described.

55 The material remaining in cinder well 20 will be coke-like unconsumed fuel and clinker. This material is elevated from the well 20 by means of the dredging bucket 27 on the crane 28 which travels upon the track 29, and by said bucket delivered into the hopper 30 of a crushing machine 31, whence the reduced material, coke and clinker, passes through a gravity separator 32, the clinker finding its way through the 60 spout 33 to the refuse or ash chamber 22,

and the unconsumed fuel or coke finding its way into the bins 34, which may constitute a part of the stoking system of stationary furnaces in a local power plant 9 (see Figures 1 and 2).

70 The crane 28 will preferably be that which is employed to fill bunkers 7 which replenish the coal supply of the locomotives as they stand over the fire-drawing pits, and to that end, track 29 will extend overhead across the greater portion of the terminal house, and the crane will be adapted to remove coal from cars on the storage tracks 12, or from a car removed from one of the 75 said storage tracks and placed beneath the crane on the through track 15. Dredge bucket 27 will also be employed for removing accumulation of ash and clinker from the settling chamber 22, and to that end will be adapted to deliver such refuse 80 to a car standing upon the track 13.

85 By the arrangement herein described, the time element, which is the most important feature in drawing the fire of a locomotive previous to moving it on to a repair station, will be amply safeguarded, in that the means for receiving the fire material is so arranged that it can serve simultaneously all of the locomotives of the system that are liable to require treatment at any one time, 90 besides coaling the tender at the same time so as to avoid the necessity of performing this step at some other point; and all these functions will be performed under conditions which will avoid interfering with the 95 working conditions of the terminal. Moreover, the fire material will be disposed of in a manner that will effect a great saving in the fuel bill at the station as well as a great saving in cost of labor.

100 Sump 24 will preferably be provided with a water supply 35 to keep up the supply of water therein, and this may if desired be located opposite a flushing outlet 36 leading to sewer, so that the sump can be washed 105 out at desired intervals.

I claim:

1. In a railway terminal, a fire disposal apparatus comprising a locomotive station, a trough-like cinder tunnel communicating 115 with said station and adapted to receive fire material from a locomotive occupying the same, and means for delivering to said tunnel a quenching and conveying body of water.

2. In a locomotive terminal, a plurality of locomotive fire-drawing stations, a cinder tunnel extending beneath and adapted to receive fire material from a locomotive occupying any of a plurality of such stations, 125 and means for delivering to said cinder tunnel a quenching and conveying body of water.

3. In a locomotive terminal, fire-drawing stations, a cinder tunnel adapted to receive 130

- fire material from locomotives occupying any of a plurality of said stations, means for delivering to said tunnel a body of water sufficient to quench and convey fire material delivered thereto, and a cinder well into which said tunnel discharges. 5
4. In a locomotive terminal, fire-drawing stations, a cinder tunnel adapted to receive fire material from locomotives occupying any of a plurality of said stations, means for delivering to said tunnel a body of water sufficient to quench and convey fire material delivered thereto, a cinder well into which said tunnel discharges, and a settling chamber into which water with suspended fire material flows from said cinder well. 10
5. In a locomotive terminal, fire-drawing stations, a cinder tunnel adapted to receive fire material from locomotives occupying any of a plurality of said stations, means for delivering to said tunnel a body of water sufficient to quench and convey fire material delivered thereto, a cinder well into which said tunnel discharges, a settling chamber into which water with suspended fire material flows from said cinder well. 15
- 20
- 25
- 30
6. In a locomotive terminal, fire-drawing stations, a cinder tunnel adapted to receive fire material from locomotives occupying any of a plurality of said stations, means for delivering to said tunnel a body of water sufficient to quench and convey fire material delivered thereto, a cinder well into which said tunnel discharges, and means for elevating and removing material from said cinder well. 35
- 40
7. In a locomotive terminal, fire-drawing stations, a cinder tunnel adapted to receive fire material from locomotives occupying any of a plurality of said stations, means for delivering to said tunnel a body of water sufficient to quench and convey fire material delivered thereto, a cinder well into which said tunnel discharges, a settling chamber into which water with suspended fire material flows from said cinder well, and means for elevating and removing material from said settling chamber. 45
- 50
- 55
8. In a railway terminal, a fire disposal apparatus comprising a locomotive station, a trough-like cinder tunnel communicating with said station and adapted to receive fire material from a locomotive occupying the same, means for delivering to said tunnel
- a quenching and conveying body of water, a sump to which water flowing through said tunnel is delivered, and means for returning water from said sump to said tunnel. 60
9. In a locomotive terminal, fire-drawing stations, a cinder tunnel adapted to receive fire material from locomotives occupying any of a plurality of said stations, means for delivering to said tunnel a body of water sufficient to quench and convey fire material delivered thereto, a cinder well into which said tunnel discharges, a settling chamber into which water with suspended fire material flows from said cinder well, a sump receiving water from said settling chamber, means for preventing the material delivered by the water to the settling chamber from passing to said sump, and means for returning water from said sump to the head of said tunnel. 70
- 75
10. In a locomotive terminal, fire-drawing stations, a cinder tunnel adapted to receive fire material from locomotives occupying any of a plurality of said stations, means for delivering to said tunnel a body of water sufficient to quench and convey fire material delivered thereto, a cinder well into which said tunnel discharges, means for elevating and removing material from said cinder well, and a cinder refining apparatus adapted to receive material from the elevating means. 80
- 85
- 90
11. In a locomotive terminal, fire-drawing stations, a cinder tunnel adapted to receive fire material from locomotives occupying any of a plurality of said stations, means for delivering to said tunnel a body of water sufficient to quench and convey fire material delivered thereto, a cinder well into which said tunnel discharges, means for elevating and removing material from said cinder well, and a cinder refining apparatus adapted to receive material from the elevating means; said means comprising a cinder crusher and a clinker separator. 95
- 100
12. In a locomotive terminal, a locomotive station, a cinder tunnel communicating with and adapted to receive fire materials from the locomotive occupying said station, a cinder reclaiming plant receiving fire material through said tunnel, a refuse disposal track leading to said terminal, and means for transferring refuse from the cinder reclaiming plant to a car on said track. 105
- 110

Signed at Chicago, Illinois, this 26th day of September, 1921.

SPENCER OTIS.
